116,561

DESIGN FOR A MERCHANTISE DISPLAY CASE

Melvin C. Houle, Chicago, Ill., assignor to Owen Housholder and David C. Cohen, copartners, doing business as Crystal Manufacturing Co., Chicago, Ill.

Application July 20, 1939, Serial No. 86,106

Term of patent 3½ years

To all whom it may concern:

Be it known that I, Melvin C. Houle, a citizen of the United States, residing at Chicago, in the county of Cook and State of Illinois, have invented a new, original, and ornamental Design for a Merchandise Display Case, of which the following is a specification, reference being had to the accompanying drawing, forming part thereof.

I claim:

The ornamental design for a merchandise display case, substantially as shown.

MELVIN C. HOULE.
